U. S. PATENT OFFICE.

No. 110.

1861.

WHOLE No. 1,475.

Trade Mark on Lead Pencils.

EBERHARD FABER, OF NEW YORK, N. Y.

Letters Patent for a Design No. 110, dated October 8, 1861.

SPECIFICATION.

TO ALL WHOM IT MAY CONCERN:

Be it known, that I, E. FABER, of No. 133 William street, in the city, county, and State of New York, have invented or produced a new and original design for Printing or Stamping upon and Ornamenting Lead Pencils; and I do hereby declare the following to be a full, clear, and exact description of the same, reference being had to the accompanying drawings making a part of this specification, in which—

Figure 1 represents a pencil, with my design stamped upon it.

Figure 2 represents the same, by an enlarged view.

The object of my invention is to ornament lead pencils, and also to form a mark by which they may be readily distinguished from all other pencils, and be thereby known in the trade; and the invention or design consists in the combination of an American or national flag, with the word "Union" placed at its side.

The flag is composed of thirteen stripes and thirty-four stars, the former being emblematical of the original compact of thirteen States, and the latter representing the number of States in the Union.

The staff, from which the flag is represented as unfurled to the breeze, is furnished on top with a spear, and inclines towards the head or top of the pencil.

The word "Union," which forms a part of my design, is placed on the right-hand side of the flag, midway between the parallel sides of the pencil, and is composed of a letter known in the trade as nonpareil Clarendon.

My design is intended to be embossed or imprinted, either plain or in gold or silver, upon the pencils themselves, near one end.

Des. 1475

Having thus described my design, what I claim as new and desire to secure by Letters Patent is,

The ornamental design or trade mark composed of an American or National Flag combined with the word "Union" as represented, to be fixed on pencils in the manner and for the purposes described.
